United States Patent Office

Des. 185,331
Patented May 26, 1959

185,331

COMBINED DIALING PENCIL AND HOLDER THEREFOR

Norbert Tannenbaum, New York, N.Y.

Application April 15, 1958, Serial No. 50,478

Term of patent 7 years

(Cl. D74—24)

Fig. 1 is a front perspective view of a combined dialing pencil and holder therefor, showing my new design; and

Fig. 2 is a rear elevational view thereof as it appears with the pencil in the holder.

I claim:

The ornamental design for a combined dialing pencil and holder therefor, substantially as shown and described.
